CIRCULATION PROCESS AND DEVICE IN
SULPHITE CELLULOSE DIGESTION

Sjune Svensson, Hissmofors, Krokom, Sweden

Application November 10, 1932, Serial No. 642,112
In Sweden October 22, 1931

25 Claims. (Cl. 92—7)

The present invention relates to improvements in and relating to digestion of fibrous material for the production of sulphite cellulose and other similar digestion processes, and particularly processes which are adapted to effect circulation of the digesting liquid in such digestion.

It has appeared that a uniform degree of attack of the digested fibrous material is obtained only when the circulating digesting liquid is drawn off in the lower portion of the digester, and is introduced in a preheated state into the upper portion of the digester. It has only been possible to practically utilize this suitable circulation on using pumps for propelling the digesting liquid through one or several circulation conduits. Tests have been made to make the digesting liquid, directly or indirectly heated, rise upward in a conduit built in the digester, and then move from the top to the bottom in the remaining part of the digester filled with fibrous material, but said tests have not led to any practical results, because by only indirect heating the necessary circulation speed is insufficient, and, moreover, the formation of incrustation cannot be avoided.

The inventor has found that the above stated suitable circulation digestion with good result and with the known advantages, which a circulation of sulphurous gas involves, may be applied, without using liquid pumps, by supplying to a circulation conduit opening into the top and bottom of the digester, which conduit the fibrous material cannot enter, a certain quantity of sulphurous gas together with the quantity of steam, if any, to be added to the digesting liquid, whereby the gas may be introduced wholly or partly mixed with steam. Said gas or gas mixture, flows upward through the conduit, and thus a suction is effected in the lowest portion of the same.

The circulation of the digesting liquid thus arisen may be increased by introducing the gas and the gas mixture respectively, and the digesting liquid in such a way that injector action arises. The circulation may also be increased in another way, for example by using pumps or compressors. In order to avoid increase of the pressure, gas may be drawn off from the upper portion of the digester to the necessary extent.

In applying the inventor's circulation method now stated it is possible to allow the digesting liquid to be heated only by direct supply of steam, mixed with gas, if desired, or to effect the heating of the digesting liquid wholly or partly indirectly either in the digester itself, or in a preheater in the circulation conduit. In the last mentioned case the formation of incrustation in the pre-

heater is counteracted by the excess of sulphurous acid in the digesting liquid.

In applying the inventor's said method it is also possible to supply preheated, or not preheated digesting liquid from another digester to the circulation conduit prior to or after introducing the gas and the gas mixture respectively. 60

The invention comprises also a process for effecting in the digestion of sulphite cellulose a circulation of the digesting liquid from the top to the bottom through the space filled with fibrous material in the digester, and from the bottom to the top in a conduit opening completely within the digester at the top and the bottom of the digester, sulphurous gas or steam, or a mixture of 65 steam and sulphurous gas being pressed into the conduit, and being mixed with digesting liquid therein under injector action. 70

Thus a very good circulation of the digesting liquid is obtained with movement from the top 75 to the bottom through the charge of chips without using power consuming pump devices.

Further the invention relates to the improvement in digesting sulphite cellulose in a digester having a circulation conduit for the digesting liquid, into which gas, or gas and steam is introduced, by introducing the gas, or the gas and the steam into the digester or the conduit at a height above the bottom of the digester corresponding at least to $\frac{1}{3}$, preferably to about $\frac{2}{3}$ of the total 80 height of the digester, in order to reduce the resistance to the circulating gas as much as possible. 85

Further the invention relates to certain means for carrying out the circulation processes in 90 question, more particularly to screens for introducing the digesting liquid into the circulation conduit, and means for introducing steam, gas, or gas mixture into the same pipe under injector action. 95

In the accompanying drawings

Figure 1 is a partial section of a digester, provided with an interior circulation conduit according to the invention.

Figure 2 is a detail section along the line 2—2 100 of Figure 1 on a larger scale.

Figure 3 is a section along the line 3—3 of Figure 2.

Figure 4 is a partial vertical section through a digester provided with means for carrying out 105 the process according to the invention.

Figures 5, 6 and 7 are details of the apparatus shown in Figure 4 on a larger scale.

Figure 8 is a horizontal section of another 110

embodiment of an apparatus, provided with means for carrying out the invention.

Figure 9 is a section along the line 9—9 of Figure 8.

5 Figure 10 is a detail of the apparatus shown in Figures 8 and 9 on a larger scale.

Figure 11 is a section along the line 11—11 of Figure 10 on a larger scale.

In Figure 1 20 indicates the digester in which 10 is located a conduit or flue 21 opening at the top and at the bottom into the digester, said conduit at a height above the bottom of the digester corresponding to about $\frac{2}{3}$ of the height of the digester being provided with a gas or steam jet 15 apparatus 22, to which are connected two supply pipes 23, 24 for supplying steam, and a supply pipe 25 for supplying sulphurous gas. The steam in the pipe 23 may preferably have a pressure of about 7 atmospheres, and in the pipe 24 of about 20 20 atmospheres. The lowest portion of the flue 21 is preferably connected to a screen device 26 located in the bottom of the digester, through which screen the digesting liquid may be drawn off in the pipe 27 when the digestion is ready. 25 The end of the flue 21 opening into the upper portion of the digester 20 is provided with a screen 28. To said screen is connected a pipe 29 opening into the uppermost portion of the digester, which pipe thus may be said to constitute 30 a continuation of the flue 21.

When the digester at the beginning of the digesting process is almost filled with digesting liquid, said continuation has for its object to effect a circulation in the digesting liquid in the uppermost portion of the digester. When later, as the digesting process proceeds, the digesting liquid sinks in the digester, and the pressure round the screen 28 becomes lower, the liquid flowing in the flue will, of course, to a larger extent enter the digester through the screen 28. In the construction of the upper portion 29 of the circulation pipe it is important to observe that the opening through which the digesting liquid passes from the pipe to the contents of the digester is made large enough so that chips outside the pipe do not check the flow too much. Provision should preferably be made that the liquid is allowed to flow downward through one or more annular openings, thus preventing chips from 45 entering the pipe.

50 In order to prevent steam from entering, and passing through the flue 21 when making the chips basic, a throttle valve 30 is located in the same, which valve is thus held throttled during 55 the basic process. The flue is preferably also held closed while the digester is being filled with the digesting liquid. The throttle valve 30 may also be disposed in such a way in the flue that the basic making steam can be supplied to the chips 60 through the flue.

The gas and steam jet apparatus 22 respectively is designed in the shape of a ring 31 (Figs. 2 and 3) which at the top and at the bottom is connected to the flue 21. The ring 31 encloses 65 several superposed canals 32, 33, 34 and 35 which are connected to the supply pipes 23 and 24. Thus each of the canals 32, 33, 34 and 35 is separately connected to the steam supply pipe 23, and adapted to be shut off by means of valves 70 36. The high pressure steam from the pipe 24 together with the sulphurous gas enters from the canal 35. The canals 32, 33 and 34 are connected to the interior of the flue 21 by means of upwardly directed, mamelonated exhaust canals 37. 75 The exhaust canals 38 of the canal 35 are not

mamelonated. If desired, the exhaust canals may be provided with removable nozzles. It is clear that the supply pipes to the gas and steam jet apparatus respectively also may be arranged for supply of only sulphurous gas or only steam, and also in such way that the gas does not meet the steam until in the flue. The steam jet apparatus may also be connected only to a steam supply pipe, and the annular canals may also in another way than as has been shown be connected to the different supply pipes. The work of the steam jet apparatus is considerably facilitated by being placed on the above mentioned height above the bottom of the digester, because the liquid column which offers the greatest resistance to the gas or the steam then becomes relatively small. The conduits for the circulation are thus also to a great extent changed from pressure conduits to suction conduits, and thus the tendency of forming gypsum occurring in pressure conduits is considerably reduced.

80 Further, due to the simple embodiment of the system, one obtains so spacious dimensions of necessary conduits and members for a relatively small cost of material that there need be no great speeds of the liquid. This fact furthers in its turn a uniform suction of the digesting liquid in the circulation conduit in which before all the natural tendency of balancing between different layers of liquid of different temperature and 90 specific gravity is utilized. The liquid obtains a smaller specific gravity in the conduit by being so to speak "impregnated" there by gas and steam. The low speed of the digesting liquid in combination with straight conduits and passages 100 counteracts considerably formation of incrustation on the interior walls of the apparatus.

110 The disposition of the steam jet apparatus within the digester makes the use of a straight system possible i. e. a system in which the digesting liquid is not drawn off from the digester to the heating source by means of pumps in order to be returned to the digester again, but in which the digesting liquid only has to pass through an almost straight pipe. The driving action of the 115 steam jet apparatus develops its highest power first when the temperature exceeds 70° C.; a centrifugal pump loses its suction capacity at the same temperature. The heat losses are very small, almost no parts being outside the digester. 120 The system also offers a very great reliability of service and low maintaining costs, no moving parts being at hand.

125 According to Figures 4, 8 and 9 an annular screen is located in the lower portion of the digester, by which screen digesting liquid may be drawn off. Screens of the prior art used in digesters consist of a perforated whole annular tube. A tube of that kind is difficult to mount and difficult to take out and drawbacks arise on account of the expansion of the material at raising temperature. The screen devices forming part of the invention are constructed in such a manner that the said 130 drawbacks are removed.

135 The screen device consists of two conduits in the embodiment shown in Figure 4, said conduits being mutually connected to a pipe 39. Each conduit consists of a number of segments 40 shaped as screen members, said segments being 140 flexibly connected by means of sleeves 41. Said sleeves 41 are provided with shoulders 42 resting against the wall of the digester so that the conduit is held at some distance from the wall. The shoulders 42 which rest loosely against the wall 145

of the digester are suitably designed in such a way that the centre of gravity of each screen segment 40 lies in a plane above the upper resting edge of the shoulders so that the conduits when expanding due to increased temperature will turn upward and outward about said edge, i. e. in the sense indicated by the arrow in Figure 7. In order to prevent the conduit from sliding downward the conduit rests against abutments 44 which are stationarily connected to a loose continuous ring 45 resting on the bottom of the digester. The abutments 44 may also be stationarily connected to the wall of the digester.

The shoulders 42 may also be adapted only 15 to rest against the abutments 44, and the conduits may rest directly with their sleeves against the wall of the digester. The conduits may also communicate with each other by means of several pipes 39.

20 The lower conduit communicates with a pipe 46 connected by means of cocks partly to the circulation conduit 47, and partly to an exhaust conduit 48.

25 The screen segments 40 consist of tube pieces which are preferably bent to fit the shape of the wall of the digester, but they may also be straight. The segments are preferably made of the same size, whereby when mounting the screen device the length of the conduit is simply adjusted after 30 the width of the superficies of the digester by cutting off the last segment. The shoulders, which also may be located at another place than on the sleeves of the tube pieces, are adjusted after the shape of the digester when mounting the apparatus. The conduit follows the wall of the 35 digester very well because the sleeves are designed so that a play exists between the tube pieces and the sleeves, and consequently a certain flexibility of the conduits is obtained.

40 Figure 5 shows a detail of a conduit in which straight tubes are used. In order to unite two screen segments a loose sleeve 41 is here used, the said sleeve being formed with a shoulder adapted to rest against the wall of the digester.

45 When using bent tube segments (Figure 6) one end is preferably shaped as a sleeve 41 in which the opposite end of the adjacent segment 40 is introduced.

50 Of course the play between tubes and sleeves the said play effecting the flexibility, must not be so large as to enable fibers to pass through same.

The tubes may either be provided with fine 49 holes and thus act as screens or with larger holes 55 members 50, preferably in the form of a cylinder, covering the said holes and formed with a perforated superficies, a very large screen face being obtained in the last mentioned case.

Instead of being round the screen device may 60 have other cross section which may be more suitable to effect less resistance against the fibrous mass on emptying the digester. The cross section may for instance be formed as a triangle one side of which rests against the wall of the 65 digester. A suitable embodiment is to arrange such a screen close to the outlet, the cross section of the said screen being of a triangular shape. The screen device may consist also of one single conduit.

70 Figures 8 and 9 show another embodiment of a screen device, comprising two hollow perforated rings, one of which is located above the other in the lower conical portion of the digester. The said rings are arranged in such a manner that all 75 liquid entering the upper ring is led to the lower

ring below the screen face of same, from where it is either led away from the digester or is led to a higher situated place in the same along with liquid flowing through the screen face into the lower ring. The said screen rings may consist 80 of segments connected by means of joints, and may be placed in the brickwork of the digester, the segments of the upper ring being made pointed at their upper ends, so that the brickwork will lie on the same level with the screen faces, which 85 highly facilitates the exhaustion of the pulp.

In the embodiment shown in the Figures 8 and 9 the screen consists partly of an upper ring formed of segments 51, connected with each other and of the same shape, partly of a lower ring formed of the segments 52 which are connected with each other and also are of the same shape. The segments are preferably locked by means of bolts and nuts applied in opposite holes of adjacent segments. The bolt is provided with a square portion right below the head of the bolt, the said portion being somewhat thicker than the thickness of the screen plate. Hereby is obtained that the different segments get a certain mobility relatively to each other. To facilitate the separation of parts the holes of one segment have a round shape and those of the other segment an oblong shape and the head of the bolt an oblong shape, the head of the bolt thus being turned that way at the locking that the longitudinal direction of the said head becomes perpendicular to the oblong hole. On separating the parts one need only unfasten the nut and turn the bolt 90°. On the side facing the interior of the digester each segment is provided with perforations and the said segment is not made larger than can be introduced through the neck opening of the digester and can be handled by one man without difficulty. Intermediate conduits 53 are placed between the two rings and distributed all 100 around, all liquid entering the upper ring being conducted through the intermediate conduit to the lower ring and therefrom away from the digester through the conduit 54, or during the digestion, in order that digesting liquid shall circulate in the digester, up through the flue 55. The intermediate conduits may preferably be perforated in order to obtain a larger screen face. The upper ring rests on stages 56 in the brickwork 105 of the digester and the lower screen ring rests 110 against a ring 57 located in the bottom of the digester.

115 Canals or recesses for the intermediate conduits 53 are arranged in the brickwork between the rings. In order to facilitate the exhaustion of 120 the pulp, the interspace between the screen rings is filled with brickwork of such a thickness that it is on the same level with the screen faces. For this purpose also the segments 51 of the upper ring have been made pointed at their upper ends. 125 The segments 52 of the lower ring may also be made pointed at their upper ends and of course one need not then fill the interspace between the rings with such a thick brickwork. The cross sections of the two rings have an extended shape 130 and follow the wall of the digester. In order that the segments shall be able to stand the pressure of the mass of the digester supports 58 are provided in each segment. The segments and the intermediate conduits may be partly limited by 135 the wall of the digester so that the same will form the bottom of each segment.

140 Figures 10 and 11 show how an intermediate conduit 53 may be applied in the brickwork between the rings.

On account thereof that this screen construction is not rigid and thereby that it is freely placed on the abutment the drawbacks caused by the expansion are removed. On occasion damage may be quickly remedied on account thereof that the screen may be easily laid apart. A good regulation for obtaining an even screen capacity is made possible.

Having now described my invention, what I claim as new and desire to secure by Letters Patent is:

1. A process for digesting sulphite cellulose consisting in circulating digesting liquid from above downwardly through the space of a digester, filled with fibrous material, and from below upwardly in a conduit, opening at the upper and lower part of the digester and into which conduit the fibrous material is prevented from entering, introducing sulphurous gas into the conduit, sucking the digesting liquid into the lower part of the conduit and pressing out said liquid into the digester from the upper part of the conduit, while leading off sufficient gas from the upper part of the digester to avoid an increase of the pressure.
2. In a process as claimed in claim 1, introducing in the digesting liquid the whole quantity of steam needed into the conduit.
3. In a process as claimed in claim 1, in which the gas is introduced into the conduit mixed with steam.
4. In a process as claimed in claim 1 indirectly heating the digesting liquid while circulating through the conduit outside the digester.
5. In a process as claimed in claim 1, introducing digesting liquid from another digester into the circulation conduit.
6. In a process as claimed in claim 1, introducing the gas into the conduit in such a manner that an injector action arises and the circulation of the digesting liquid is furthered thereby.
7. In a process as claimed in claim 1, introducing the gas along with steam into the conduit in such a manner that an injector action arises and the circulation of the digesting liquid is furthered thereby.
8. A process for digesting sulphite cellulose, consisting in circulating digesting liquid from above downward through the space of the digester filled with fibrous material and from below upward in a conduit located entirely inside the digester and open at its upper and lower ends into which conduit the fibrous material is prevented from entering, forcing sulphurous gas from a source located outside the digester into the conduit and mixing therewith the digesting liquid under injector action.
9. A process for digesting sulphite cellulose, consisting in circulating digesting liquid from above downward through the space of the digester, filled with fibrous material and from below upward in a conduit located entirely inside the digester and open at its upper and lower ends into which conduit the fibrous material is prevented from entering by forcing a mixture of sulphurous gas and steam from a source located outside the digester into the conduit and mixing therewith the digesting liquid under injector action.
10. A process for digesting sulphite cellulose, consisting in circulating digesting liquid from above downward through the space of the digester, filled with fibrous material and from below upward in a conduit located entirely inside the digester and open at its upper and lower ends into which conduit the fibrous material is prevented from entering, forcing partly steam, part-

ly sulphurous gas from a source located outside the digester into the conduit and mixing therewith the digesting liquid under injector action.

11. A process for digesting sulphite cellulose consisting in circulating the digesting liquid together with sulphurous gas mixed with steam from above downward through the space of the digester, filled with a fibrous material, and from below upward in a conduit opening at the upper and the lower ends of the digester, while introducing the gas into the digester at a height above the bottom of same, corresponding to between $\frac{1}{3}$ to $\frac{2}{3}$ of the total height of the digester.

12. In combination with a sulphite digester, a device comprising a conduit opening at the upper and the lower end of the digester, a screen at the lower end of the conduit, means for introducing sulphurous gas mixed with steam and causing digesting liquid to be sucked into the lower part of the conduit through said screen and forcing said liquid into the digester from the upper part of the conduit.

13. In combination with a sulphite digester, a device comprising a circulation conduit which opens at the upper and the lower end of the digester, a jet apparatus formed at a suitable place on the conduit and a plurality of supply pipes leading to the jet apparatus at least one of said supply pipes being connected to a gas injector with inlet for steam, the other supply pipes being connected with supplies for steam and valves on said pipes adapted to close the pipes.

14. A combination with a sulphite digester, a device comprising a circulation conduit which opens at the upper and the lower ends of the digester, a jet apparatus in the shape of a ring enclosing a plurality of superposed canals, which communicate with the supply pipes, at least one of said supply pipes being adapted for a gaseous fluid and from which canals, directed obliquely to vertical exhaust canals, open into the interior of said ring, the ring being at its upper and lower ends connected to the circulation conduit.

15. In combination with a sulphite digester having a circulation conduit opening at the upper and the lower conical ends of the digester, a device comprising a screen element located in said lower conical end connected to the circulation conduit, consisting of tubular screen segments, by means of sleeve joints connecting with each other to form several conduits extending around and along the wall of the digester, the said conduits being connected with each other by means of pipes, and supports for said pipes arranged inside the digester.

16. In combination with a sulphite digester having a circulation conduit opening at the upper end and the lower conical portion of the digester, a device comprising a screen element located in said lower conical portion connected to the circulation conduit, consisting of tubular screen segments, by means of sleeve joints connected with each other to form at least one conduit extending around and along the wall of the digester, supports arranged inside the digester for said segments, each screen segment consisting of a perforated tube, a screen member surrounding each tube, preferably in the form of a covering cylinder with a perforated superfcies.

17. In combination with a sulphite digester having a circulation conduit opening at the upper end and the lower conical portion of the digester, a device comprising a screen element located in said lower conical portion connected to the circulation conduit, consisting of tubular

- screen segments, by means of sleeve joints connected with each other to form at least one conduit extending around and along the wall of the digester, supports arranged inside the digester 5 for said segments, shoulders located on the conduit, the said shoulders resting loosely against the wall of the digester and being shaped in such a manner that the centre of gravity of each screen segment is located in a plane above the 10 upper resting edge of the shoulders, in order that the conduit, when expanded due to increased temperature, may be able to turn upward and outward around the said edge.
18. In combination with a sulphite digester 15 having a circulation conduit opening at the upper end and the lower conical end of the digester, a device comprising a screen element located in said lower conical end in the form of two hollow perforated rings one located above the other and 20 arranged in such a manner that all liquid entering the upper ring is led away to the lower ring below the screen face of the same and from there along with the liquid flowing through the screen
- face into the lower ring leaves through an outlet, connected to the circulation conduit.
19. A device as claimed in claim 18, in which a plurality of intermediate conduits are arranged between the upper and lower ring. 80
20. A device as claimed in claim 18, in which said rings consist of segments connected with each other by means of joints. 85
21. A device as claimed in claim 18, in which each screen ring rests on stages in the wall of the digester.
22. A device as claimed in claim 18, in which at least the upper ring is pointed at its upper end.
23. A device as claimed in claim 18, in which the cross sections of both rings are of an oblong shape and closely follow the wall of the digester. 90
24. A device as claimed in claim 18, in which brickwork with canals for the intermediate conduits fills the interspace between the rings. 95
25. A device as claimed in claim 18, in which the rings are partly limited by the wall of the digester.
